ATTORNEY

UNITED STATES PATENT OFFICE

FREDERICK D. REYNOLDS, OF ST. LOUIS, MISSOURI

SHOE PLATE

Application filed February 20, 1931. Serial No. 517,199.

This invention relates to new and useful improvements in shoe plates, the primary objects of the invention being the provision of a shoe plate which effectively protects the toe of the sole and which is adjustable to fit shoes of various sizes and shapes.

Other objects of the invention are to provide a shoe plate having a marginal upstanding flange adapted to fit against and protect the edges of the toe end of the sole and provided with an inwardly and horizontally disposed perforate flange adapted to fit against and be secured to the underside of the sole.

Still other objects of the invention are to provide a shoe plate for protecting the edge of the sole which consists of a vertically disposed marginal flange of substantially the same height as the thickness of the sole and of a horizontally disposed inwardly projecting flange by means of which said shoe plate is secured to the underside of the sole, said horizontal flange being provided with raised convex surfaces for engaging the floor so as to prevent the edges of said flange from coming in contact therewith.

Further objects of the invention are to provide a shoe protector which is of horseshoe shape and right-angled in cross section, the upstanding flange fitting against the edge of the toe and of the sole and the horizontal flange fitting against the underside thereof, the last mentioned flange being provided with a plurality of spaced radially disposed slots to permit bending of the shoe protector to fit shoes of various sizes and shapes.

Still further objects of the invention are to provide a shoe protector of the class described, one end of said horizontal flange having formed integral therewith a central plate which is substantially semi-circular in shape and provided with a convex face so as to provide a central bearing point for the shoe.

With these and other objects in view, my invention consists in certain novel features of construction and arrangement of parts, hereinafter more fully described and claimed.

and illustrated in the accompanying drawing, in which—

Figure 1 is a bottom plan view of a shoe equipped with my improved shoe plate.

Figure 2 is an enlarged vertical cross section taken on line 2—2 of Figure 1.

Figure 3 is an enlarged top plan view of the shoe plate before attachment thereof to a shoe.

Figure 4 is a similar view but showing the shoe plate in contracted position.

Figure 5 is a top plan view of a modified form of shoe plate.

As is well known in the art, metallic toe protectors covering the toe of the upper of the shoe have been generally used. However, these protectors are secured below the upper to the upper face of the sole and do not afford protection to the latter. Furthermore, such protectors are very conspicuous and unsightly in appearance and they have to be made in various sizes to fit various shoes as they are not adjustable. Also such toe protectors require considerable time and skill in securing them in position.

My present invention contemplates the provision of a shoe plate which is used to protect the sole only and which does not extend upwardly beyond the upper face thereof. Therefore, my shoe plate or protector does not affect the appearance of the shoe and can be easily attached in position.

Referring by numerals to the accompanying drawing, 10 indicates a shoe plate which is substantially of horseshoe shape having a central curved portion 11 and end portions 12. In cross section the plate is angular, having a vertically disposed marginal flange 14 and a horizontally and inwardly presented flange 15. The marginal flange 14 is of a height equal to or slightly less than the thickness of the sole so that the upper edge of said flange does not extend beyond the upper face of the sole (see Fig. 2). The width of the horizontal flange 15 is such that a row of protuberances 16 can be formed thereon in spaced relation with each other and with the edges of said flange. These protuberances are of circular shape and have convex outwardly presented faces so that only smooth

rounded surfaces come in contact with the floor.

As shown, each protuberance is formed with a central depressed portion 17 having an aperture 18 for receiving nails 19. Thus the plate can be readily nailed against the underside of the sole and the heads of the nails are received in depression 17 and cannot come in contact with the floor.

10 In order to eliminate the necessity of carrying a large assortment of shoe plates to accommodate shoes of various sizes and shapes, my improved shoe plate is formed adjustable and can be bent to fit the particular shoe. To 15 this end the horizontal flange 15 is provided with a plurality of spaced radially disposed slots 20. These slots which open inwardly are preferably V-shape to provide the necessary clearance when contracting the plate.

20 The inner edge of the flange 15 is preferably turned upwardly, as indicated at 15^a, to insure a close contact thereof with the sole and prevent sharp edges from marring the floor.

25 Preferably one end of the edge 15 has formed integral therewith a central piece 21. This is semi-circular in shape and has a central raised or convex portion 22 and a plurality of semi-circular ridges 24 formed concentric with the former. A plurality of apertures 25 is formed between the rows of ridges 24 whereby said central piece can be secured to the sole by nails passing through said apertures.

35 The purpose of this central piece 22 is to provide a central bearing point when the shoes are used for stage dancing.

As the central portion 22 is connected at one point only to the flange 16 it does not 40 interfere with the shaping or adjustment of the plate.

I claim:

1. A metallic toe plate comprising an arcuate member right-angled in cross section and 45 having its vertically disposed marginal flange adapted to fit against the edge of the toe portion of the sole of a shoe, said member having its horizontal flange formed with a plurality of spaced raised portions centrally apertured 50 to receive nails for securing said plate to the underside of said sole of the shoe, said horizontal flange being formed with a plurality of V-shaped slots which permit said toe plate to be bent inwardly to conform with the curvature of the toe portion of said sole, and a 55 central semi-circular piece formed integral with one end of said horizontal flange and disposed centrally of said plate, said central piece being provided with a convex face to provide a central bearing point for the forward end of the shoe.

2. A metallic toe protector for shoes comprising a U-shaped member right-angled in cross section and having its vertically disposed marginal flange fitting against the edge

of the toe portion of the sole of a shoe, and having its horizontally disposed flange fitting against the underside of said sole, said horizontal flange being provided with a plurality of spaced inwardly opening V-shaped 70 slots whereby said member can be bent to fit the contour of the toe portion of the sole, said horizontal flange being provided with a plurality of circular convex portions having central apertures for receiving nails by means 75 of which said member is secured to the sole, there being a central circular piece formed integral with one end of said horizontal flange and extending transversely of the ends of said member and arranged centrally thereof, said central piece being provided with a convex face to provide a central bearing point for the toe portion of the shoe, and having a plurality of apertures arranged in spaced relation in the peripheral flange of said central 80 piece for receiving means for securing said flange in position.

In testimony whereof I hereunto affix my signature this 14th day of February, 1931.

FREDERICK D. REYNOLDS.
